DESIGN FOR A TRAFFIC SIGNAL

John J. Hammer, Detroit, Mich.

Application April 12, 1946, Serial No. 128,552

Term of patent 3½ years

(Cl. D72—1)

To all whom it may concern:

Be it known that I, John J. Hammer, a citizen of the United States, residing at Detroit, in the county of Wayne and State of Michigan, have invented a new, original, and ornamental Design for a Traffic Signal, of which the following is a specification, reference being had to the accompanying drawing, forming a part thereof, in which:

Fig. 1 is a side elevational view of a traffic signal embodying the invention; and

Fig. 2 is a top plan view.

Fig. 1 of the drawing has been lined for color. The device is symmetrical and is the same when viewed from any side thereof shown in the drawings.

I claim:

The ornamental design for a traffic signal, substantially as shown and described.

JOHN J. HAMMER.
